(57) **CLAIM**

The ornamental design for a vehicle grille as shown and described.

DESCRIPTION

FIG. 1 is an isometric view of a vehicle grille, showing our new design;

FIG. 2 is a partial enlarged detail view of portion shown in FIG. 1.

FIG. 3 is a front elevational view thereof; and,

FIG. 4 is a rear elevational view thereof.

Stippling in the drawings represent the three-dimensional contours of the design, and is not intended to indicate surface decoration. The broken lines shown in the drawings depict portions of the vehicle grille that form no part of the claimed design. The dash-dot broken lines in FIGS. 1-3 define boundaries of the claim and form no part of the claimed design.
